UNITED STATES PATENT OFFICE

CHARLES E. ATTWOOD, OF JAMESTOWN, NEW YORK, ASSIGNOR TO POSTINDEX COMPANY, INC., OF JAMESTOWN, NEW YORK, A CORPORATION OF MASSACHUSETTS

PAPER FILE

Application filed February 27, 1930. Serial No. 431,747.

This invention relates to paper files of the class in which the sheets are arranged with their identification-receiving margins in overlapping relationship so as to present all of their margins to view at one time, whereby the name, subject matter or numerical indexes of the sheets may be scanned quickly, without manipulating the same. In some files of this class, the sheet capacity of a file 10 of given dimensions is multiplied by placing a plurality of sheets on each sheet carrier. The present invention is concerned with a file of this latter type, having a novel and improved construction and arrangement of 15 the sheets on each carrier, whereby any desired sheet may be offset or shifted laterally to distinguish it from other sheets.

The invention will best be understood by reference to the following description, when 20 taken in connection with the accompanying drawings of one specific embodiment thereof, while its scope will be pointed out more particularly in the appended claims.

In the drawings:

Fig. 1 is a front elevation of a file embodying the invention;

Fig. 2 is a sectional view of the panel on a much enlarged scale on line 2—2 of Fig. 1, with a sheet carrier, minus the sheets, in 25 place in the panel;

Fig. 3 is an elevation of one of the sheet carriers with two folded sheets thereon, one sheet being offset laterally with relation to the other;

Fig. 4 is a sectional view on an enlarged scale on line 4—4 of Fig. 3;

Fig. 5 is a similar, sectional view, also on an enlarged scale on line 5—5 of Fig. 3;

Fig. 6 is an elevation of one of the sheet carriers with two sheets thereon, offset relatively to each other, with one of the sheets turned through an angle of 180 degrees from its normal position;

Fig. 7 is an elevation similar to Fig. 6, but with each sheet offset to a position opposite to that shown in Fig. 6;

Fig. 8 is an elevation of one of the carriers with its sheets, illustrating the mode of removing one of the sheets from the carrier;

50 and

Fig. 9 is an elevation of the carrier after the removal of the first sheet, and illustrating the mode of removing the second sheet.

Referring to the drawings, and to the embodiment of the invention which is illustrated therein, and having reference at first more particularly to Figs. 1 and 2, there is shown a paper file comprising a mounting conveniently in the form of a sheet-metal panel 11, which, as shown in Fig. 2, presents sheet-carrier guides 12, having channels 13 beneath or behind inwardly directed flanges 14. As shown, the panel is also provided with transverse upper and lower, inwardly-directed flanges 15 and 16 (see Fig. 1), which close the upper and lower ends of the channels. Referring again to Fig. 2, the channels receive appropriate sheet carriers which, in the present example, are resilient wires 17, having terminal spacing enlargements 18 to space the wires and to predetermine the exposure or overlap of the margins of the sheets presently to be described. The wire, being resilient, may be sprung to reduce the length of the carrier, thereby to permit the removal of the latter from the channels.

Referring now to Fig. 3, one of the carriers is shown with two folded sheets 19 and 20 thereon. The sheet 19 presents two leaves 21 and 22, and the sheet 20 presents two leaves 23 and 24. While the sheets are provided with what is known as a cut index, it is deemed unnecessary to describe the same herein, because it has no particular bearing on the present invention. It should simply be understood that the sheets carried by each carrier are provided with one or more index-receiving margins, and that the margins are arranged in overlapping relationship, as shown in Fig. 1. The sheets are normally in an upstanding position with respect to their carriers, as shown in Fig. 1, but may be turned to depending positions, and in Fig. 3 this latter position is shown.

Referring now to Fig. 9, the sheet 19 is provided with two perforations 25, through which the carrier is passed, and these perforations are intersected by the line of the fold. The sheet 20 (see Fig. 8) is similarly provided with two perforations 26, through

which the carrier is passed, and these perforations are likewise intersected by the fold. From a comparison of Figs. 8 and 9, it will be observed that, while the perforations 25 are symmetrically located with reference to the lateral edges of the sheet 19, and the perforations 26 are symmetrically located with reference to the lateral edges of the sheet 20, yet the spacing of the perforations of one sheet differs from the spacing of the perforations of the other sheet,—that is to say, the perforations 25 are nearer to each other than the perforations 26 are to each other. This enables the two sheets to be placed on one carrier, without nesting the sheets together, and also enables the sheets to be offset relatively to each other on the carrier. It should, of course, be understood that the width of each sheet between its lateral edges must be very substantially less than the distance between the spacing projections 18 on the sheet carrier.

Referring to Fig. 6, it will be observed that the sheet carrier extends first within the fold of the sheet 20 through one of the perforations 26, then along the outside of both sheets, then through one of the perforations 25 of the sheet 19, then within the fold of the latter, thence through the second perforation 25, then along the outside of both sheets, then through the second perforation 26 of the sheet 20, and finally within the fold of the sheet 20. One result of this arrangement is that the two sheets, instead of being nested together, are disposed as well illustrated in Figs. 4 and 5. Another result of this arrangement is that each of the sheets can be shifted or offset laterally with relation to the other in a manner which will be evident from a comparison of Figs. 6 and 7, in which one of the sheets has been swung through an angle of 180 degrees, to lie in the same plane as the other. The amount which the sheets can be offset with relation to each other is of course determined by the difference in spacing of the perforations of one sheet from the spacing of the perforations of the other sheet. It will be noted that when the sheets are offset, the distance from one perforation 25 to the next adjacent perforation 26 is approximately twice the amount of offset,—that is to say, twice the distance between two adjacent lateral edges of the sheets.

The mode of removing the sheets from a carrier will readily be understood from an examination of Figs. 8 and 9. The first step is to open or unfold the sheet 20, as shown in Fig. 8. The carrier may now be shifted a short distance toward the right, as shown in Fig. 8. The next step is to bend or flex the sheet 20 along the line A—A to bring the adjacent perforation 26 into a plane substantially perpendicular to the carrier, whereupon the adjacent spacer 18 may be

withdrawn through the perforation by shifting the sheet 20 laterally toward the left. Finally, the sheet 20 is shifted toward the right, and is flexed along the line B—B, to permit the right-hand spacer 18 to be drawn through the right-hand perforation 26. Removal of the sheet 19 from the carrier is accomplished in a similar manner by first opening or unfolding the sheet, then flexing the latter along the line C—C to permit the left-hand spacer 18 to be withdrawn through the left-hand perforation 25. Either spacer may then be withdrawn through the right-hand perforation 25, without flexing of the sheet, by simply moving the spacer into a position approximately at right-angles to the plane of the sheet, and then removing the carrier lengthwise. The sheets may be reassembled with the carrier by a reversal of the foregoing operation.

Having thus described one embodiment of the invention, but without limiting myself thereto, what I claim and desire by Letters Patent to secure is:—

1. In a file, the combination of a sheet-carrying wire, and two sheets carried by said wire, said sheets and said wire having cooperative means by which said sheets are attached to said wire and can be moved independently of each other lengthwise of said wire.

2. In a file, the combination of a sheet-carrying wire, and two sheets carried by said wire, each sheet being provided with two perforations through which said wire extends, the space between the perforations of one sheet differing from the space between the perforations of the other sheet.

3. In a file, the combination of a sheet-carrying wire, and two sheets carried by said wire, each sheet being provided with two perforations through which said wire extends, the perforations of each sheet being symmetrically located with relation to the lateral edges thereof, and the perforations of one sheet being spaced differently from the perforations of the other sheet.

4. In a file, the combination of a sheet-carrying wire, and two folded sheets, each provided with two perforations intersected by the fold and differently spaced, said wire extending through the perforations of each sheet, said wire being received in the fold of the sheet having the lesser spacing of the perforations between the perforations of such sheet, and being received in the fold of the other sheet between the lateral edges of such sheet and the perforations.

5. In a file, the combination of a sheet-carrying wire, and two folded sheets, each provided with two perforations intersected by the fold and differently spaced, said wire extending through the perforations of each sheet, said wire being received in the fold of the sheet having the lesser spacing of the

perforations between the perforations of such sheet, and being received in the fold of the other sheet between the lateral edges of such sheet and the perforations, and the perforations of each sheet being symmetrically located with reference to the lateral edges of such sheet.

5 6. In a file, the combination of a plurality of sheets, a sheet carrier, said carrier and 10 said sheets having cooperative means by which said sheets are attached to said carrier, said means having provision to permit said sheets to be moved laterally relatively to each other and relatively to said carrier.

15 7. In a file, the combination of a plurality of sheets, an elongated sheet carrier, said carrier and said sheets having cooperative means to permit said sheets to be moved relatively to each other and relatively to said carrier lengthwise of the latter.

20 8. In a file, the combination of a plurality of sheets, a sheet-carrying wire, said sheets being provided with perforations through 25 which said wire extends, the perforations in each sheet differing in location from the location of the perforations of another sheet, thereby to permit one sheet to be moved relatively to another sheet on the said wire lengthwise of said wire.

25 9. In a file, the combination of a plurality of sheets, a sheet-carrying wire, said sheets being provided with perforations through 30 which said wire extends, the perforations in one sheet being spaced from each other differently from the spacing of the perforations of another sheet.

35 In testimony whereof, I have signed my name to this specification.

CHARLES E. ATTWOOD.
